PRODUCTION OF SLIVER

Ludwig Schlippe, Kassel, and Max Boettie, Kassel-Bettenhausen, Germany, assignors to Spinnfaser Aktiengesellschaft, Kassel-Bettenhausen, Germany, a corporation of Germany

Application July 7, 1938, Serial No. 217,878
In Germany February 14, 1938

8 Claims. (Cl. 19—99)

This invention relates to apparatus for manufacturing from cellulose wool a sliver which is capable of being drawn and can be spun directly without a subsequent combing operation.

5 As is well known, the longer and better sorts of wool are worked and spun in the so-called worsted yarn process and the so-called top or combed material is the most important trade product. After the wool has been steeped, washed, cleaned and prepared in any other suitable manner, it is treated in a roller card to obtain a card sliver which is capable of being drawn and is combed in the combing machine while permanently doubling and drawing it, so as to lay 10 the fibres parallel, to remove the neps and "nits," such as impurities, undesirable formations, small knots and the like and to remove the comber waste or noils. The ideal sliver so obtained, the so-called top or combed material, which consists 15 only of relatively long, well-loosened and parallelly arranged fibres and lends itself very well for drawing, is now usually subjected to the draw-spinning process.

This invention has for its object the production 20 from cellulose wool of a sliver which is equivalent to this combed wool material.

Another object of the invention is to produce a sliver which renders the combing operation unnecessary, and forms a very voluminous yarn.

30 With these and further objects in view which will hereinafter appear, our invention consists not only of the structures herein pointed out and illustrated by the drawing, but relates to further structures as hereinafter may be claimed.

35 The character of the invention, however, may be best understood by reference to one of its structural forms, as illustrated by the accompanying drawing, showing in Fig. 1 a schematic side view of our novel machine and in Figs. 2 and 40 3 details of Fig. 1, on a larger scale.

Referring to the drawing, it will be seen that a support or table 14 carries by means of rollers 16 an endless feed lattice 1 for the card which comprises a machine frame 15 carrying pairs of fluted rollers 2 and a shell feeder plate 3 for feeding the cellulose wool to picking rollers 17 which in turn transfer the material to a taker-in or licker-in 4 which feeds the material to the main cylinder or swift 5 of a specially constructed card.

50 This card, in accordance with the invention, is a "mixed" or combined card comprising a roller and clearer card portion (which is sometimes also referred to as a worker and stripper card) and a revolving flat card portion, and the worker and clearer rollers 7 and 8 being arranged before the

flat chain 6, which is guided, in the manner known per se, over rollers 18, 19, 20, 21. It is also possible to use several pairs of worker and clearer rollers which are constructed to effect a preliminary loosening of the long-fibred spinning material and to prevent larger fibre balls from entering between main cylinder and flat. The flat card portion in turn is mainly constructed to parallelize and straighten the fibres and to remove neps and "nits" therefrom. Hence it rather takes 10 over the function which in the wool industry is carried out by the combing machine.

It will thus be understood that we do not use the revolving flat card which is practically used exclusively in the cotton fine yarn industry, nor the roller card used in the wool industry and in the cotton coarse spinning, nor a combination "half roller card, half flat card" having stationary flats in the card portion, but our novel machine is a "half roller—half revolving flat card."

According to a special feature of our invention, the flat chain 6, in order to give reliable service for working cellulose fibres of 50 mm. length and more, has flats 9a and 9b of different types of covering which are arranged alternately and at predetermined distances. One type of covering, 9a, is of the conventional type and fitted with pins 24 the ends of which are inclined at angles of, for example, 74°, with respect to the flat surface, against the pins of the main cylinder, as best seen 30 in Fig. 2, while the other type of covering, 9b, is fitted with pins 23 the ends of which are directed at angles of substantially 90° to the flat surface, as best seen in Fig. 3. Thus, the flats 9a will exert a normal carding action, while the flats 9b will 35 exert only a slight carding action or rather a stroking and straightening action. One or more flats 9b are arranged between two successive flats 9a which are spaced from each other at intervals corresponding at least to the maximum length of 40 staple of the fibres. Thus, it will be understood that a single fibre in spite of its relatively great length will not be acted upon by two flats 9a at the same time, whereby difficulties would be caused in view of the said great length of the 45 fibres, but the fibres are rather guided and held parallel only between two successive flats 9a, by the intermediate flat or flats 9b.

When working material of medium length, e. g. of 50, 60 or 70 mm. length, one flat with the new 50 stroking clothing is arranged between two flats having normal clothing; in the case of still longer fibre material two, three or several flats with stroking clothing may be inserted between two flats with normal clothing.

The essential advantage of this process consists in the fact that the flats with the stroking clothing have a carding action to a limited extent without these flats however preventing those fibres which are held back on one of the carding flats, being able to be smoothly stroked out by the cylinder. When there is no possibility of smooth stroking out rapid clogging of the flat cards takes place. Since the vertically disposed hooks, exerting more of a stroking action, also maintain a carding action, although a weakened one, the working of fibres having a staple shorter than 50 mm. is also possible on the same machine. There is in addition sufficient carding action, impairment of the fibres, moreover, being particularly well avoided. In this connection it is of importance that the curling of the fibre, which plays an important part for the working of cellulose wool, is extremely well protected when using the new cards.

Arranged at the rear end of the flat is a flat stripping apparatus 25 and a doffing comb 22 for removing the material from the flat.

Mounted on the main frame 15 in series with the main roller 5 and in contact therewith is a doffer 10 which is acted upon by a doffing comb for combing the web from the surface of the doffer 10. A funnel 12 for condensing the web to a sliver is further mounted on the main frame 15. A separate coiler 26 serves for collecting the sliver.

We do not propose to use a fancy or fly roller, as we have found that in our novel machine the same would cause entangling of the fibres. Instead of a fancy, we provide a system of clearer rollers 13 at the lower side of the fleece-free main cylinder 5, before the taker-in 4. The direction of rotation of the various parts of the machine is indicated by the arrows in Fig. 1. Our novel process for treating cellulose wool will now be described with reference to our aforescribed machine as follows:

The endless cellulose wool is advantageously cut to a length of staple over 50 mm., dried, and fed over the lattice 1, through the pairs of fluted rollers 2, the shell feeder plate 3 and the picking rollers 17 to the taker-in 4 which in turn delivers the material to the main roller 5. The spinning material is now first preliminarily loosened in the worker and clearer rollers 1 and 8 and formed into a web, and is then straightened and freed from neps and nits between the revolving flat 6 and the main roller 5, in such a manner that the flats 9a have a more intensive or normal carding action while the flats 9b have only a slight carding action and stroke and straighten the fibres only, as hereinbefore described.

The fleece or web is then transferred to the doffer 10 from which it is removed by the doffing comb 11 and fed to the calendering apparatus or condensing funnel 12.

The sliver so obtained may be collected in conventional manner in a can 26 and packed or delivered directly to spinning machines of the kind known, for instance, in worsted yarn manufacture, avoiding the use of a combing machine. The sliver prepared in this careful manner is well straightened, clean and free from neps and nits so that it corresponds at this stage of the process to a high-quality combed material and can be spun immediately, without being subjected to a combing process, and consequently it preserves substantially its curliness and elongation and forms a very voluminous yarn.

While we have herein shown and described certain preferred embodiments of our invention, we wish it to be understood that we do not confine ourselves to all the precise details herein set forth by way of illustration, as modification and variation may be made without departing from the spirit of the invention or exceeding the scope of the appended claims.

More particularly, we wish to make it clear that our invention is not restricted to the special construction of the card portion which has been hereinbefore described. Fundamentally we use flats of normal type of covering having a strong combing or carding action, combined and alternating with flats having less combing or carding and more stroking or fibre guiding action, due to their hooks or pins or other members retaining the fibre material less intensively.

The coverings of the flats are preferably constructed as hereinbefore described but they may be modified in any suitable manner provided only that an effect similar to that which has been hereinbefore described is attained.

We claim:

1. In a machine for treating textile fibres, in combination, a rotatable main cylinder, means for feeding staple fibres thereto, a roller card portion comprising worker and clearer rollers cooperating with the cylinder to effect carding of staple fibres fed thereto and a flat card portion comprising a card chain having flats spaced from each other at intervals corresponding at least to the maximum length of fibre and covered with inclined pins, and flats intermediate said first flats, and covered with pins whose free end portions are at substantially right angles to their base.

2. In a machine for treating fibres, a main cylinder, worker and clearer rollers in co-acting relation with said main cylinder, a card chain following said rollers and having spaced first flats covered with inclined pins, and second flats between said first flats and covered with pins whose free end portions are at substantially right angles to said second flats, a doffer following said main cylinder and, following said doffer, means adapted to condense the web of fibres to a sliver.

3. In a machine for treating fibres, a shell feeder plate, a taker-in, a main cylinder, worker and clearer rollers in co-acting relation with said main cylinder, a card chain following said rollers and having spaced first flats covered with inclined pins and second flats between said first flats and covered with pins whose free end portions are at substantially right angles to said second flats, a doffer following said main cylinder and, following said doffer, means adapted to condense the web of fibres to a sliver.

4. In a machine for treating fibres, a feed lattice, at least one pair of fluted rollers, a shell feeder plate, a taker-in, a main cylinder, worker and clearer rollers in co-acting relation with said main cylinder, a card chain following said rollers and having spaced first flats covered with inclined pins and second flats between said first flats and covered with pins whose free end portions are at substantially right angles to said second flats, a doffer following said main cylinder and, following said doffer, means adapted to condense the web of fibres to a sliver.

5. In a machine for treating fibres, a card chain having spaced first flats covered with pins whose free end portions are inclined obliquely thereto, and second flats arranged between the

first flats and covered with pins whose free end portions extend at substantially right angles to the surface of said second flats.

5. A card chain as set forth in claim 5, wherein the distance between consecutive first flats is greater than the average length of the fibres worked upon.

10. In a machine for treating fibres, in combination, a carding cylinder, a roller card portion comprising worker and clearer rollers cooperating with the cylinder, means for feeding fibres to said cylinder immediately in advance of said rollers, and a flat card portion comprising a traveling card chain having alternately arranged flats provided with pins of different inclination and arranged to receive the web of fibres conveyed from the worker and clearer rollers.

15. first flats and covered with pins whose free end portions extend at substantially right angles to the surface of said second flats.

have been partially carded at the roller card portion.

8. In a machine for treating fibres, in combination, a carding cylinder, a roller card portion comprising worker and clearer rollers cooperating with the cylinder to effect carding of fibres fed thereto, means for feeding fibres to said cylinder immediately in advance of said rollers, and a flat card portion comprising a traveling card chain having alternately arranged flats provided with pins of different inclination and arranged to receive the web of fibres conveyed from the worker and clearer rollers.
